UNITED STATES PATENT OFFICE

92,798

DESIGN FOR A CLASP OR SIMILAR ARTICLE

Amson Furtach, New York, N. Y.

Application October 24, 1933, Serial No. 49,541

Term of patent 3½ years

To all whom it may concern:

Be it known that I, AMSON FURTACH, a citizen of the United States, residing in the city, county and State of New York, have invented a new, original, and ornamental Design for a Clasp or Similar Article, of which the following is a specification; reference being had to the accompanying drawing, forming part thereof.

Fig. 1 is a front view of a clasp or similar article showing my new design, with the elements of the clasp interconnected.

Fig. 2 is a side view thereof.

Fig. 3 is a front view of the clasp or similar article shown in Fig. 1, with the elements disconnected.

I claim:

The ornamental design for a clasp or similar article as shown and described.

AMSON FURTACH.
